UNITED STATES PATENT OFFICE

JOSEPH SILVERMAN, OF CHICAGO, ILLINOIS

FOLDING CHAIR

Application filed April 4, 1927. Serial No. 180,701.

This invention relates to folding chairs and its objects are the provision of a generally improved and simplified brace structure for bracing the chair against the up and down, 5 diagonal and other stresses which are imposed, and a brace structure which will fold compactly into the plane of the frame of the chair and which will permit folding and unfolding of the chair, as well as accommodate 10 itself compactly and effectively to the folded and unfolded positions of the chair.

The invention is illustrated in the accompanying drawings, in which

Fig. 1 is a vertical section through a chair 15 embodying the present invention, showing the chair in open or unfolded position for use and taken on the line 1—1 of Fig. 2;

Fig. 2 is a fragmentary rear elevational view with the chair in open or unfolded position;

Fig. 3 is a fragmentary elevational view looking towards the bottom of the seat of the chair in folded position; and

Fig. 4 is a fragmentary vertical section 25 taken on the line 4—4 of Fig. 3 and showing the chair in folded position.

While the present invention is not limited to a particular chair, it has been found particularly advantageous in connection with 30 the chair structure disclosed in my co-pending application, Serial No. 172,321, filed March 3, 1927, and I have, for purposes of illustration, shown the invention in connection with the chair structure of the foregoing applica- 35 tion.

Referring to the drawing, the chair shown comprises generally an inverted U-shaped frame 10, having parallel sides 12, closed at the top and open at their lower ends at 14. 40 The lower free ends 14 of the sides of the frame 10 form one pair of legs of the chair.

A second pair of legs 16 are pivoted between their ends at 17 between and to the opposite sides 12 of the frame 10. A seat 18 fits be- 45 tween the sides 12 of the frame 10 and has fixed pivotal connection at each of its opposite sides with the sides 12 at 19. The seat 18 also has sliding pivotal connection through bars or links 20 and a suitable rod 21 with 50 the upper ends of the pivoted legs 16. The

lower leg forming ends 14 of the sides 12 and the legs 16 may be braced crosswise or transversely by cross braces 23 and 24, as in the application above referred to.

The frame 10, legs 16 and cross braces 23 and 24, selected for illustration, are of the construction disclosed in my co-pending application, Serial No. 128,737, filed August 12, 1926. The upper surface of the seat 18 may be padded and covered as desired. 55

The fixed pivots 19, which pivotally secure the opposite sides of the seat to the sides 12 of the frame 10 may be in the form of rivets passing through the flat intermediate webs of the sides 12 of the frame, and through the depending vertical side flange 25 of the seat. The opposite ends of the rivets 18 may be permanently headed, or removable nuts may, of course, be provided to permit detachment of these connections, if desired. 60

One of the bars or links 20 is disposed on the inside of each side of the seat frame 25, and preferably up in the plane of the depending flange 25, as shown in Fig. 1. The bars 20 have depending flanges 28, which are disposed vertically when the chair is unfolded; as shown in Fig. 1, and at their rear ends the bars 20 are pivoted to the frame 10 and seat frame 25 through the pivotal connections 19. 65

The outer or free ends of the bars 20 are 70 curved to conform with the rounded corners of the seat frame 25 and are detachably secured to the depending flange of the seat frame as by means of bolts and nuts 29. The flat intermediate webs at the upper ends of 75 the legs 16 are cut away at 30 and the upper ends of one of the tubular sides or marginal edges of the legs 16 are cut away at 32 to permit the inner end of the seat to swing between the sides 12 of the frame 10 and into 80 the plane of the frame when the chair is folded. The other tubular margin of each leg 16 continues upwardly at 33.

The pivotal and sliding connection between the upper ends of the legs and the seat of 85 the chair is formed by the cross rod 21 which extends transversely across the bottom of the seat frame 25 and through longitudinal slots 35 in the depending flanges 28 of the bars 20. Outwardly of the flanges 28, the rod 21 at 90

each side of the chair is offset at 36 and turned generally at right angles and extend into the tubular extensions 33 of the legs 16. The ends of the rods may be suitably secured in the tubular extensions 33 of the legs 16, or they 5 may extend out across the legs, as more fully set out in the first of my co-pending applications.

The notches 38 in the rear corners of the 10 seat frame, for receiving the tubular extensions 33 of the legs 16 when the chair is folded, so that the seat and legs will assume a parallel relation and lie between the sides 12 of the frame 10 and in the plane of the frame 10 when the chair is folded, may be formed by 15 angular cuts in the flange 25 at the opposite rear corners and by bending or striking the freed tongues 40 inwardly, as shown.

To fold the chair, from the open position 20 shown in Fig. 1, the outer end of the seat 18 is swung upwardly about the pivots 19 into position between the sides 12 of the frame 10 and in the plane thereof, as shown in Fig. 4. This upward swinging of the seat 25 18 is accompanied by a combined pivotal and sliding action of the rod 21 in the slots 35, the upper ends of the legs 16 closing into the plane of the seat frame and the transverse pivotal and sliding portion of the rod 21 sliding 30 inwardly in the slots 35 to the position shown in dotted lines in Fig. 4, whereupon the legs 16 and seat 18 are disposed parallel and both between and in the plane of the frame sides 12.

35 The brace means with which the present invention is particularly concerned, comprises a pair of diagonal braces 42 and 43. These braces 42 and 43 are preferably formed of metallic strips, the widths of which extend in the direction of the widths of the sides 14 of the frame 10. They cross one another substantially centrally between the sides of the frame at 45 and are preferably twisted or turned to dispose their widths 40 where they cross at 45 generally normal to the direction of extension of the width of the frame sides 14. The crossing portions 45 are secured together, as by means of a rivet 46.

50 The upper ends of the cross braces 42 and 43 are turned to lie parallel with the frame sides 14 and one between each of the sides and the adjacent side of the frame 25. These upper ends are apertured and pivoted at 48 upon the pivotal connections 19. Just below the pivoted ends 48 (Fig. 3) the braces 42 and 43 are rounded at 50 to conform with the rounded inner corners of the seat frame and to receive the inner end of the seat frame 55 between the upper ends of the braces so that the braces and seat frame may all lie substantially parallel and in the plane of the sides 12 of the frame 10 when the chair is folded.

60 65 The lower ends (Fig. 3) of the braces 42

and 43 are turned at 52 to lie adjacent and parallel with the legs 16. The lower parallel ends 52 of the braces are provided with longitudinal slots 53 through which slots these lower ends of the braces have pivotal and sliding connection with the legs 16 through pins or rivets 54, the shanks of which extend through the slots 53 and are suitably secured in the legs 16. The inner ends of the pins or rivets 54 may be headed and the opposite ends may be riveted into the legs 16. Suitable spacers may be provided on the shanks of these pins or rivets 54 between the legs 16 and the parallel lower ends 52 of the cross braces 42 and 43.

When the chair is folded, the braces 42 and 43 receive the rear end of the seat between them at their upper ends and lie substantially parallel with the seat and substantially parallel with the sides 12 of the frame 10 and between and in the plane of the frame 10. They permit and accommodate themselves to the compact folding action in the other parts of the chair and, as the chair is unfolded for use, these braces 42 and 43 swing about the pivots 19 and 54 at their opposite ends into the generally vertical positions shown in Fig. 1. The swinging of the lower ends of the braces 42 and 43 in the unfolding or opening of the chair is accompanied by a sliding action of the lower slotted ends 52 downwardly upon the pins or rivets 54, and the folding of the chair is accompanied by an upward sliding action of these lower ends 52 with an accompanying pivotal action on the pins 54 and an accompanying pivotal action between the upper ends of the braces 42 and 43 and the seat frame 25 and frame 10 to close or fold the braces 42 and 43 into the plane of the frame 10.

100 In an actual embodiment of the invention, I find that the braces 42 and 43 effectively brace and strengthen the chair and particularly the seat against up and down stresses, as well as against diagonal stresses from either side and the various other stresses which are imposed upon the chair.

105 The lower ends of the legs 14 and 16 are preferably provided with feet or buffers in the form of blocks 80, preferably of rubber or the like. Any other suitable feet than those shown may of course be provided.

I claim:

110 1. In a folding chair, a first pair of legs, a seat pivoted thereto to swing upwardly therebetween, a second pair of legs pivoted to said first legs at a point other than the pivot of the seat on said first legs and having sliding pivotal connection with such seat and brace means pivoted at the pivoted connection 115 between the seat and said first legs and having sliding pivotal connection with said second legs, said brace means interposing a bracing action between the seat pivot and said second legs and disposed substantially wholly below 120

the upwardly folding portions of the seat and below the seat pivot in folded and unfolded positions.

2. In a folding chair, a first pair of legs, 5 a seat having pivotal connection therewith, a second pair of legs pivoted to said first legs and having sliding pivotal connection with said seat, and a pair of diagonal cross braces folding in a plane parallel with the plane of 10 fold of the seat and having their upper ends extending between said first legs and the opposite sides of the seat and pivoted upon the pivotal connections therebetween, said brace means interposing a bracing action between 15 the seat pivot and said second legs and disposed substantially wholly below the upwardly folding portion of the seat and below the seat pivot in folded and unfolded positions.

3. In a folding chair, a first pair of legs, 20 a second pair of legs, a swinging seat having a seat pivot on one pair of legs and cross braces having pivotal connection with one pair of legs at the seat pivot and sliding pivotal connection with the other of said pairs 25 of legs, said second pair of legs having pivotal connection with said first legs and sliding pivotal connection with said seat and said cross braces interposing a bracing action between the seat pivot and said last referred to 30 legs and disposed substantially wholly below the seat pivot in folded and unfolded positions.

4. In a folding chair, a first pair of legs, a second pair of legs, a swinging seat having 35 a seat pivot on one pair of legs and cross braces having pivotal connection with one pair of legs at the seat pivot and sliding pivotal connection with the other of said pairs of legs, said second pair of legs having pivotal 40 connection with said first legs and sliding pivotal connection with said seat and said cross braces having fixed angular relation with respect to each other and each extending diagonally between the leg of one pair of legs 45 on one side of the chair and the opposite leg of the other pair of legs on the opposite side of the chair.

In witness whereof, I hereunto subscribe my name this 31st day of March, 1927.
JOSEPH SILVERMAN.
